UNITED STATES PATENT OFFICE

158,552

COMBINED WALL BRACKET AND VAPORIZER CASING

Emil Buehler, North Haledon, N. J., assignor to
American Aerovap, Inc., a corporation of New
York

Application July 22, 1948, Serial No. 147,703

Term of patent 14 years

(Cl. D16—2)

To all whom it may concern:

Be it known that I, Emil Buehler, a citizen of the United States, and residing at North Haledon, in the county of Passaic and State of New Jersey, have invented a new, original, and ornamental Design for a Combined Wall Bracket and Vaporizer Casing, of which the following is a specification, reference being had to the accompanying drawing, forming part thereof, and in which

Fig. 1 is a perspective view of a combined wall bracket and vaporizer casing, showing my new design.

Fig. 2 is a top plan view thereof, and
Fig. 3 is a side elevation thereof.

I claim:

The ornamental design for a combined wall bracket and vaporizer casing, as shown.
EMIL BUEHLER.
